CONTROL APPARATUS

Application filed June 16, 1927. Serial No. 199,146.

Our invention relates generally to control apparatus and more particularly to cam-actuated switches.

The object of our invention, generally stated, is to provide a contactor having a snap action which is relatively simple in construction, effective in operation and economical to manufacture.

A more specific object of the invention is to provide for a snap action in cam-actuated contactors.

Other objects of the invention will, in part, be obvious, and will, in part appear hereinafter.

15 The invention, accordingly, is disclosed in the embodiment thereof shown in the accompanying drawings, and comprises the structural features and the combination of elements and arrangement of parts which will 20 be exemplified in the construction hereinafter set forth and the scope of the application of which will be indicated in the claims.

For a more complete understanding of our invention, reference may be had to the following detailed description, taken in conjunction with the accompanying drawings, in which

Figure 1 is a view, in side elevation, of a contactor constructed in accordance with our invention and showing the relative positions of the different members of the contactor when it is open;

Fig. 2 is a view, in side elevation, of the contactor showing the relative positions of the members when the contactor is in its closed position; and

Fig. 3 is a top plan view of the contactor shown in Figs. 1 and 2.

Referring to the drawings, the contactor 40 comprises a base member 1 made of some suitable insulating material, a stationary contact-carrying member 2 mounted on the base 1 and a cooperating movable contact-carrying member 3 which is pivotally supported in a frame member 4 secured to the base 1. As shown, latching members 5 and 6 for locking the movable contact-carrying member in different positions are also mounted in the frame 4.

50 A cam 7 for effecting the operation of the

contactor is arranged to operate the mechanism associated with the movable contact-carrying member 3. In this particular embodiment of our invention, we have illustrated the stationary contact-carrying member 2 mounted upon the base member 1 and secured thereto by a bolt 8 which is also utilized to secure a blow-out coil 9 and arcing horns 11 disposed adjacent to the contact tips.

A contact tip 12 is pivotally mounted on the stationary contact-carrying member 2 by means of a pin 14. As shown, a spring 15 is interposed between the contact-carrying member 2 and the contact tip 12 to bias the latter toward a predetermined position.

The bracket or frame 4 may be of any suitable design, but, in the embodiment shown, in order to facilitate the mounting of the movable contact-carrying member 3, the frame is shaped to simulate a channel member. The movable contact-carrying member 3 is pivotally mounted in the frame 4 by means of a pin 16.

In order to operate the movable contact-carrying member 3, a pivotally-mounted actuating arm 18 and a spring 21 are provided. As shown, the actuating arm 18 is pivotally mounted at 19 in the forward end of the frame 4, and the spring 21 is tensioned and utilized to connect the actuating arm 18 to the contact-carrying member 3. Pins 22 and 23 are provided on the arm 18 and member 3, respectively, to facilitate the mounting of the spring 21.

In Figs. 1 and 2, a cam wheel 7 is shown rotatably mounted on shaft 24 and disposed in alignment with a roller 25 which is mounted on a depending projection formed integral with the actuating arm 18. In such construction, any suitable means, not shown, may be provided for actuating the shaft 24 to oscillate the actuating arm 18, and therefore, shift the line of action of the spring 21.

As has been set forth hereinbefore, the spring is disposed to connect the movable contact member 3 and work arm 18. The dead-center line for the spring 21 extends through the pins 23 and 16. Therefore, when the spring 21 is moved across this line, the

actuating arm 18 is biased in the same direction. However, since the pin 23 cannot move into alignment with, or above, the pivot point of the actuating arm 18, the spring 5 continuously biases the arm 18 toward the cam wheel 7.

In order to effect a snap action of the movable contact member 3 to break quickly any circuit and thereby reduce arcing to a minimum, provision is made for locking the contact-carrying member 3 until the point of connection of the actuating arm 18 and the spring 21 has crossed dead center and almost reached the limit of its movement. The locking of the member may be effected in many ways and, in this case, latches 5 and 6 are provided.

The latches 5 and 6 are hook-shaped members and are pivotally supported in the frame 4 by means of pins 26 and 27. A spring 38 is extended between the latches to bias them into engagement with a pair of lugs 28 and 29 provided on projections 31 and 32, respectively, formed on movable contact member 3. As illustrated, the latches 26 and 27 are so shaped as to overlap the lugs 28 and 29 and are disposed to be operated by actuating arm 18. When the arm 18 is moved back and forth, it will engage overlapping extensions 33 and 34, provided on the latches 5 and 6, to disengage them from the lugs 28 and 29 on the movable contact member 3.

A shunt 35 is provided on the contactor for connecting the movable contact member 3 to the binding post 39, and a similar shunt 36 is connected to the stationary contact tip 12 and its support.

Assuming that the contactor is in open-circuit-making position, as illustrated in Fig. 1, the work arm 18 stands in its lower position. In this position, the latch 5 engages the lug 29, and the movable contact-carrying member is locked in its lower position.

Upon the operation of the cam wheel 7, the work arm 18 is rotated counter-clockwise about its pivot point 19, and the spring 21 is carried through its dead-center position. As soon as the spring passes dead-center, it functions to bias the contact-carrying member to its upper or circuit closing position, and the tension on the spring 21 becomes greater until the projection 41 on the work arm 18 engages the overlapping extension 34 on the latch 5 and disengages it from the lug 29 on the movable contact member 3, whereupon the contact-carrying arm 3 is moved to its upper position with a snap action.

When the contactor is closed, the roller 25 on the work arm 18 will rest on the outer periphery of the cam wheel 7, and the contactor will remain closed so long as the roller 25 remains in this relative position. However, when the cam is rotated, and the roller 65 25 reaches the point where the radii of the

cam 7 decreases, the work arm 18 will shift its position responsive to the tension in the spring 21, causing the spring 21 to pass from a position biasing the contact members 2 and 3 into engagement, through its dead-center position, to a position urging the contact members apart.

However, the latches 5 and 6 associated with the movable contact member 3, being constantly urged into engagement therewith, the latch 6 retains the movable contact 3 closed. The contactor remains closed and the movable contact member 3 in its circuit-closing position until projection 42 on the work arm 18 engages the extension 33 on the latch 6 and disengages the latch 6 from the locking lug 28. The movable contact member will then be caused to snap open to interrupt the circuit.

It will be noted that the contact tip 12 is mounted and supported in contact with a spring 15 to permit a rolling action which reduces the arcing and sparking between the tips 12 and 13 when the circuit is interrupted. Further, it will be readily appreciated that, through the operation of the latching means which is provided to restrain the movement of the movable contact-carrying member until the actuating spring is biased a predetermined amount, practically any degree of speed may be imparted to the movable contact member 3, depending upon the strength of the actuating spring 21 and the place where the latches are disengaged, the purpose being to rapidly interrupt the circuit and reduce the arcing between the contact tips 12 and 13 to a minimum.

By mounting the shunts 35 and 36 on the contactor, (as illustrated) at the points where the least amount of whipping action will be imparted to them, the life of the shunts will be greatly increased. It will also be noted that, by connecting the spring between the pivoted contact-carrying member 3 and the work arm 18, as illustrated, the spring functions to produce a rapid opening motion to the switch as well as a rapid closing motion.

While the illustrated example constitutes a preferred embodiment of our invention, we do not limit ourselves strictly to the details herein shown, since, manifestly, the same may be considerably varied without departing from the spirit of the invention, as defined in the appended claims.

We claim as our invention:

1. A circuit-interrupting device comprising a frame, a stationary contact member carried by the frame, a movable contact member disposed to engage the stationary contact member, the movable contact member being pivotally mounted on the frame, resilient latching members disposed to engage the movable contact member, an arm pivotally mounted on the frame for operating the movable contact member, a cam member for actu-

ating the arm resilient means connecting the freely movable ends of the cam actuated arm and the movable contact member, said resilient means being disposed to bias the movable contact member to different positions in response to the movement of the cam actuated arm and to cause said arm to continuously react against the cam, and means operated upon the actuation of said arm for operating the latching members to release the movable contact member when the arm reaches different predetermined positions, to utilize the resilient means in actuating the movable contact member.

10 2. A circuit-interrupting device comprising a frame, a stationary contact member carried by the frame, a movable contact member pivotally mounted on the frame, resilient latching members disposed to engage the 15 movable contact member, a cam, an arm actuated by the cam for operating the movable contact member, resilient means connecting the cam actuated arm, and the movable contact member, said resilient means being disposed 20 to bias the contact member to different positions upon the operation of said cam, and being further adapted to retain the arm in engagement with the cam, and further means operated upon the actuating of said cam for 25 disengaging the latching members to release the movable contact member when the cam reaches different predetermined positions to utilize the resilient means in actuating the movable contact member.

30 3. A circuit-interrupting device comprising, in combination, stationary and movable contact members, resilient means for actuating the movable contact member to different positions, an arm disposed for oscillatory movement for changing the line of application of force by the resilient means to effect the operation of a movable contact member, means for locking the movable contact member in different positions and a cam for actuating the oscillatory arm, said arm being disposed to effect a release of the locking means and said resilient means being disposed to bias the arm into engagement with the cam continuously.

35 4. In testimony whereof, we have hereunto subscribed our names this 31st day of March, 1927, respectively.

EDWARD E. ROSE.
JOHN T. WELSH.
